UNITED STATES PATENT OFFICE.

NATHAN LIEBERFREUND, OF NEW YORK, N. Y.

EAR-RING FASTENING.

SPECIFICATION forming part of Letters Patent No. 790,965, dated May 30, 1905.

Application filed March 10, 1905. Serial No. 249,359.

To all whom it may concern:

Be it known that I, NATHAN LIEBERFREUND, a citizen of the United States, residing at New York city, Manhattan, county and State of New York, have invented new and useful Improvements in Ear-Ring Fastenings, of which the following is a specification.

This invention relates to an improved ear-ring fastening which is safe, of simple construction, and may be readily manipulated.

In the accompanying drawings, Figure 1 is a side view of an ear-ring provided with my improved fastening, showing it closed; Fig. 2, a similar view, showing it open; Fig. 3, a rear view; Fig. 4, a longitudinal section on line 4-4, Fig. 3; Fig. 5, a cross-section on line 5-5, Fig. 4; Fig. 6, a rear view of the guard; and Fig. 7, a front view of Fig. 6, partly in section.

20 The letter *a* represents the head or setting of an ear-ring which may be of suitable construction and design. From the head *a* projects rearwardly an ear-wire *b*, provided near its free end with an inclined hook or beak *b'* and with a finger-piece *b''* back of said beak.

To the bottom of head *a* is fulcrumed by a stop-hinge *c'* a guard-wire *c*, which may be made in the form of a bail, the rear arm of which is longer than the front arm. This 30 rear arm is provided near its upper end with an upright slot *c'*, adapted for the passage of the free end of wire *b*, together with its hook *b'*. Below the slot *c'* there is formed in the guard *c* a perforation or rear indentation *c''*, adapted to be engaged by hook *b'*, so as to form a catch. The length of the slot *c'* should be sufficient to permit hook *b'* to be brought into engagement with perforation *c''*, Fig. 4. In order to guide the end of the ear-wire *b* 40 toward the slot *c'*, the rear arm of guard *c* is provided on its inner face with a longitudinal

groove *c*, within which the slot *c'* is centered, Fig. 7.

In use the guard *c* is opened, Fig. 2, the ear-wire is passed through the ear-lobe, and 45 the guard is swung up until the hook *b'* is projected through the slot *c'* and snaps into the rear perforation *c''*, Figs. 1 and 4. Thus the fastening will be closed, the parts being held in engagement by a slight dip of the ear-wire coöperating with a rearward spring of 50 the guard caused by the action of the stop-hinge *c'*. To open the fastening, the ear-wire *b* is slightly raised by its finger-piece *b''*, and the rear guard-arm is simultaneously pushed 55 forward, when the hook *b'* will be withdrawn from the perforation *c''*, and the guard may be swung down, Fig. 2.

It will be seen that my improved fastening, though readily opened and closed by the 60 wearer, requires such a peculiar manipulation that any unauthorized or accidental opening is prevented.

What I claim is—

1. In an ear-ring, an ear-wire having a 65 beak, combined with a guard-wire having a slot adapted for the reception of the ear-wire, and a perforation below the slot adapted to be engaged by the beak, substantially as specified.

2. In an ear-ring, an ear-wire having a 70 beak, combined with a guard-wire which is longitudinally grooved on its inner face and has a slot centered within said groove, and a perforation below the slot, substantially as 75 specified.

Signed by me at New York city, Manhattan, New York, this 9th day of March, 1905.

NATHAN LIEBERFREUND.
